UNITED STATES PATENT OFFICE.

EUGENE ROBERTS BARBER, OF VALDOSTA, GEORGIA.

CONVEYER FOR BOTTLED SODA-WATER.

1,075,893.

Specification of Letters Patent.

Patented Oct. 14, 1913.

Application filed July 31, 1912. Serial No. 712,510.

To all whom it may concern:

Be it known that I, EUGENE R. BARBER, a citizen of the United States, and a resident of Valdosta, in the county of Lowndes and State of Georgia, have invented a new and Improved Conveyer for Bottled Soda-Water, of which the following is a full, clear, and exact description.

It is a design of my invention to provide a means for conveying soda water in bottles, in bottling works, from the different tables or from automatic bottling machines, to any point in the plant where the goods are to be examined, labeled and packed, ready for sale or shipment. The handling of bottled soda water involves special difficulties not met with in the mere handling of empty bottles, because in the case of bottled soda water, the bottles are subject to explosion by reason of rough handling, by the bottles coming in contact with a metal, or other hard surface, or from a fall on a hard surface, or from the bottles falling against each other.

My invention has also for its design, the production of a conveying means that will prevent the bottles from being jarred either against each other, or against any hard object in a way that might cause an explosion.

The invention further has for its design, the production of a conveying means for the purpose indicated, in which the filled bottles will be carried to a revolving table, and the provision of means associated with the table to prevent the bottles from being jammed on the table, should the removal of the bottles by the labelers or examiners be interrupted while the operation of the conveying means is permitted to continue.

The distinguishing features of my invention, and the important structural elements characterizing the preferred embodiment which is illustrated as an example, will be more particularly explained in the specific description hereinafter to be given.

Reference is to be had to the accompanying drawings forming a part of this specification, in which similar characters of reference indicate corresponding parts in all the views.

Figure 1 is a side elevation of a machine showing one embodiment of my invention, parts being broken away; Fig. 2 is a plan view; Fig. 3 is an elevation at right angles to Fig. 1, with parts in section, on about the

line 3—3 of Fig. 2; and Fig. 4 is a fragmentary view on an enlarged scale showing a guiding and distributing attachment associated with the table, to prevent the bottles from being jammed.

In constructing the machine embodying my invention, a suitable framework 10 is provided on which is mounted for rotation, a vertical shaft 11 carrying at its top a circular table 12, adjacent to which table and fixed to any convenient portion of the frame is a vertical guard rim 13, extending around the outside of the table 12, in close relation thereto for nearly a complete circle, leaving an opening or throat 14, to which throat leads a conveyer belt 15. At the throat 14 and bridging the gap between the conveyer 15 and the table 12, is a horizontal rotary disk 16, pivoted at its center as at 17 on an upright stud 18, said disk overlapping both the table 12 and the conveyer belt 15, and adapted to be rotated frictionally by the movements of said belt and table.

Any suitable means may be provided for rotating the table and actuating the belt; in the example given the table is provided with peripheral rack teeth 19, meshing with which is a spur pinion 20 on a short vertical shaft 21, said shaft having a pulley 22. A cross belt 23 extends around the pulley 22, and over a drive pulley 24 on a drive shaft 25, the various shafts being mounted in suitable bearings on the frame of the machine.

The upper stretch of the conveyer belt 15 travels in the direction of the table 12 and runs over the bottom 26 of a runway, the vertical sides 27 of which guide the bottles one of which is indicated by dotted lines at 28, the bottles passing from the belt onto the disk 16, and then to the table 12, as indicated at 28^a. The belt 15 is of soft material, such as leather, fabric, or other non-metallic material, and at the end adjacent to the table 12, the belt passes over a broad drive pulley 29, the lower stretch 15^a of the belt passing beneath said pulley 29, and between the same and a pulley 30, the latter being mounted on a shaft 31 that has bearing blocks 32 supported on springs 33 that tend to force the bearing blocks 32 upward to exert pressure on the lower run of the belt, causing the latter to be gripped between the upper and lower pulleys 29, 30 sufficiently tight to be driven. The pressure on the belt may be regulated by screws 34 that take against the upper ends of the blocks 32. At

the opposite end the belt runs over a pulley 35 mounted on an auxiliary frame 10^a that supports also the outer end of the runway 26, 27. The driving shaft 25 of the pulley 5 29 and the shaft 31 of the pulley 30 are geared together by spur gears 36, 37, fixed on said shafts.

The rotation of the table 12 carries the bottles away from the disk 16 as fast as 10 they are received on the table, and, in order that the bottles may not become jammed on the table, nor jarred against each other, an attachment is provided whereby as the bottles are carried around the table after 15 having been received, they will be directed toward the center. Thus a horizontal arm 38 supported on the standard 39 from the frame 10 extends inwardly and overhangs above the table 12, and on said arm are arranged 20 depending blades, three of which are indicated in the example shown. The blades are designated by the numerals 40, 41 and 42, and the successive blades are separated by an increasing distance toward the 25 center, there being in practice, more than three employed. The arm 38 is supported sufficiently high above the table to permit the bottles to pass therebeneath, and the depending blades on said arm incline from 30 the arm inwardly so as to deflect the bottles contacting therewith toward the central portion of the table. Thus the guard rim 13 prevents the bottles from being carried outward beyond the edge of the table, and the 35 blades 40, 41 and 42 prevent the bottles from jamming on the outside and cause them to move toward the center without violent contact with each other.

In practice the feed of the bottles to the 40 table is not greater than the attendants can handle, but the table has such a capacity that any temporary suspension in the work of the attendants in removing the bottles from the table while the conveyer continues 45 to operate and deliver bottles, will simply serve to collect the bottles on the table, first

at the center and then gradually adding to the collected bottles until the table is filled.

It will be observed that the belt, even the upper run or stretch thereof, is not under 50 tension, as the arrangement of the drive devices makes the belt essentially a loose one. The belt has support on the bottom of the runway and cushions the moving bottles carried thereby. In practice, the bottles are 55 taken from the various bottling machines or bottling tables and placed on the conveyer belt, which is of a length to reach the various bottling machines or tables in the plant.

Having thus described my invention, I claim as new and desire to secure by Letters Patent—

1. The combination with a rotary table, 60 of a conveyer belt leading to the table, and a rotary disk overlapping the conveyer and table, to transfer bottles from the conveyer to the table, and said device being in contact with the belt and table and the contact serving to rotate said device.

2. In a machine for handling bottled soda water and other bottled goods, the combination of a rotary table, means for conveying bottles to the table, including a runway leading in the direction of the table, and 65 having a bottom and sides, an endless flexible belt having its upper stretch running on the bottom of the runway and traveling in the direction of and adjacent to the table, means for actuating said belt, and a plane 70 revolving disk overlying the belt and disposed beneath a side of the runway at the end adjacent to the table, so that any portion of the said surface may receive an advancing bottle from the runway.

In testimony whereof I have signed my name to this specification in the presence of two subscribing witnesses.

EUGENE ROBERTS BARBER.
